Inventor:
Joseph P. O'Neill.
By: *Frank J. Haran*
Attorney.

UNITED STATES PATENT OFFICE.

JOSEPH P. O'NEILL, OF ST. LOUIS, MISSOURI.

COMBINED HAND REST, CARD HOLDER, AND STRAIGHTEDGE.

Application filed August 17, 1925. Serial No. 50,646.

My invention relates to a combined hand rest, card holder and straight edge especially designed for the use of bookkeepers, and has for its object to provide a device which is a distinct and practical improvement to overcome certain practical objections to, and defects in, the present type of bookkeeper's hand rest.

A further object of my invention is to provide a one piece metallic hand rest so constructed as to be capable of being moved laterally between the leaves of a book so as to bring the hand rest section below the page on either side of the book upon which entries are to be made near the bottom thereof.

A further object of the invention is to provide the device with supporting arms spaced such a distance apart as to permit one of the arms to be positioned upon the upper face of an upper page of the book to act as a straight edge for ruling purposes.

A still further object of the invention is to provide a device having a channeled or dished hand rest which when in reversed position acts as a card holder for the bookkeeper while making entries in a book therefrom.

A still further object of the invention is to provide the free end of each arm of the device with a rounded outer corner having a beveled edge to permit rapid insertion of the arms between book pages.

A still further object of the invention is to provide the front and rear walls of the hand rest section of the device with cut-away sections to provide finger holds.

A still further object of the invention is to provide a device of the character set out which possesses advantages in points of simplicity, efficiency, and at the same time prove itself comparatively inexpensive in point of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein

like characters of reference denote similar parts throughout the several views:—

Fig. 1 is a plan view of a blank of metallic stock showing portions cut away to provide spaced supporting arms.

Fig. 2 is a side elevation of the device after the hand rest section has been bent or pressed into shape.

Fig. 3 is a top plan view of Fig. 2.

Fig. 4 is an end elevation of the device.

Fig. 5 is an end elevation of the device.

Fig. 6 is a view in perspective showing the device used as a hand rest when applied to a book. The full lines show the device positioned on one side of the book and the dotted lines indicate the position thereof when shifted to the opposite half of the book.

Fig. 7 is a view in perspective of the device as applied to a book when used as a card holder.

Fig. 8 is a view in perspective of the device as applied to a book when used as a straight edge.

In carrying out the aim of my present invention, I employ a rectangular blank or sheet of suitable metallic stock designated A, as shown in Fig. 1. The blank may be of any desirable length, width and gauge.

I provide the blank A with a cutaway portion 1 which extends back from one edge of the blank a suitable distance and I also cut away, as at 2, a marginal edge section of the blank on opposite side of the cutaway portion 1 to provide two suitably spaced arms 3 and 4. The outer corner of the free end of each arm 3 and 4 is cut away to provide the curved or rounded edge 5 which is beveled from opposite sides, as at 6, to provide the pointed edge 7.

The lower or solid section of the metallic stock is bent along the transverse dotted lines 8 and 9 to provide the hand rest plate 10 and the plate reinforcing ribs or flanges 11 and 12 along its upper and lower edges, respectively.

The lower rib or flange 12 is a little higher than the top rib or flange 11 so as to extend below the lower plane of the supporting arms 3 and 4 and the lower edge of the flange 12 is bent outwardly at a right angle to the rib 12 to provide a foot 13 to

rest upon the desk or table after the arms 3 and 4 have been inserted between opposite pages of a book to act as a hand rest for a bookkeeper while making entries on lines 5 near or at the lower edge of the book pages.

Owing to the spaced arrangement of the supporting arms 3 and 4, it is evident that the hand rest section 10 of the device can be readily disposed opposite the lower edge of 10 either the left or right hand pages 14 or 15 of a book B by merely shifting or sliding the arms 3 and 4 sideways between book pages through the hand rest section 10, thereby providing a hand rest for either 15 page of the book upon which entries are being made by merely shifting the device sideways, thus obviating the necessity of withdrawing the supporting arms 3 and 4 from between pages on one side of a book and 20 reinserting them between the pages on the opposite side of the book when entries are to be made on a page on the opposite side of the book. By reference to Fig. 6 of the drawing, it will be observed that when the 25 hand rest 10 is opposite the lower edge of page 14, the device will be in the position shown in full lines so that entries can be readily made on page 14. It will be observed that when the device is in the position 30 shown in full lines in Fig. 6, that the left hand arm 3 will be positioned between pages near the left hand edge of the book with the right hand arm 4 positioned near the center of the book and between pages 35 on the other half of the book and vice versa when the hand rest has been shifted to the right half of the book.

The hand rest plate section 10 is provided with an opening 16 for hanging the 40 device up on a nail or like element and the upper and lower ribs or flanges 11 and 12 are each provided with a cutaway section 17 to act as a finger hold to permit the device to be picked up or raised from a desk or 45 table by means of the bookkeeper's fingers.

When the device is to be used as a card 50 holder for holding cards bearing data to be entered into the book, the arms 3 and 4 are inserted between the pages on opposite halves of the book, as shown in Fig. 7. When the device is used as a card holder, it 55 will be observed that it is used just reverse from that as a hand rest, that is the device is positioned opposite the top of the hook with the hand rest turned upside down so as to convert the hand rest into a channeled plate or tray for holding the cards thereupon. The upper and lower ribs or flanges prevent the cards from falling or 60 sliding off of the holder.

When the device is used as a straight edge 65 for ruling or like purposes, one of the supporting arms is positioned between the page on one side of the book and the other arm is positioned upon the page to be ruled, as

shown in Fig. 8. If desired, one or both of the arms 3 and 4 may be provided with suitable graduations 18 representing a ruler.

From the foregoing specific description of the construction of the device, it is evident, briefly, that I employ a suitable sheet of metallic stock, bifurcated at one end thereof and provide the opposite end with a channel 70 75 80 running at a right angle to the bifurcation which channel provides an elevated hand rest section when positioned right side up and a card holder when positioned upside down, which renders the device as especially useful to bookkeepers or clerks in connection with work upon ledgers, or record books of all kinds requiring entries to be constantly made therein, such as in banks, offices, commercial houses, schools and the like.

The many advantages of the herein described invention will readily suggest themselves to those skilled in the art to which it appertains.

I do not wish to be understood as having limited myself to the details of construction 90 shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall 95 within the scope of the appended claims 100 when fairly construed.

What I claim is:—

1. In a device of the class described, a single sheet of bifurcated metallic stock to provide a pair of spaced arms and said stock being channeled adjacent the inner ends of the arms to provide an arm rest when positioned one side up and to provide a card holder when positioned the other side up.

2. In a device of the class described, a single sheet of metallic stock, said sheet of metallic stock having a cutaway portion extending from one edge to provide a pair of spaced arms, a flange directed at right angle to said arms, a hand rest section directed at a right angle to the flange and in parallel relation with the arms, a flange directed at a right angle to the hand rest section and disposed parallel with and opposite said first mentioned flange.

3. In a device of the class described, a single sheet of metallic stock, said sheet of metallic stock having a cutaway portion extending from one edge to provide a pair of spaced arms, graduations upon said arms, a flange directed at right angle to said arms, a cutaway portion in said flange to serve as a finger hold, a hand rest section directed at a right angle to the flange and in parallel 125 130

relation with the arms, said section having an opening therein to permit hanging up of the device, a flange directed at a right angle to the hand rest section and disposed parallel with and opposite said first mentioned flange and a cutaway portion in said flange to serve as a finger hold.

4. In a device of the class described, a single sheet of metallic stock, said sheet of metallic stock having a cutaway portion extending from one edge to provide a pair of spaced arms, graduations upon said arms, a flange directed at right angle to said arms, a cutaway portion in said flange to serve as a finger hold, a hand rest section directed at a right angle to the flange and in parallel relation with the arms, said section having an opening therein to permit hanging up of the device, a flange directed at a right angle to the hand rest section and disposed parallel with and opposite said first mentioned flange, a short flange directed outwardly from the last mentioned flange and said last two mentioned flanges being provided with a cutaway portion adapted to serve as a finger hold for picking up the device.

5. In a device of the class described, a single sheet of metallic stock, said sheet of metallic stock having a cutaway portion ex-

tending from one edge to provide a pair of spaced arms, the outer corner of the free end of each arm being curved and beveled to provide a knife edge to permit the rapid insertion of the arms between the pages of a book, said sheet of metallic stock being channeled adjacent the inner ends of the arms to provide an elevated hand rest when in one position and to provide a card holder when in the opposite position.

6. In a device of the class described, a single sheet of metallic stock, said sheet of metallic stock having a cutaway portion extending from one edge to provide a pair of spaced arms, the outer corner of the free end of each arm being curved and beveled to provide a knife edge to permit the rapid insertion of the arms between the pages of a book, said sheet of metallic stock being channeled adjacent the inner ends of the arms to provide an elevated hand rest when in one position and to provide a card holder when in the opposite position and cutaway portions in the flanges of the channeled hand rest section to provide finger holds.

In testimony whereof, I have hereunto signed my name to the specification.

JOSEPH P. O'NEILL.
